HAIR DRYER

Earl E. Sutton, Mansfield, and Richard B. Hall, Cincinnati, Ohio, assignors to Dominion Electric Corporation, a corporation of Ohio

Filed May 10, 1962, Ser. No. 70,071

Term of patent 14 years

(Cl. D86—10)

FIG. 1

FIG. 2

FIG. 3

FIG. 4

FIG. 5

FIGURE 1 is a top and front perspective view of a hair dryer showing our new design as it appears in closed position;

We claim:

The ornamental design for a hair dryer, substantially as shown.
